ATTORNEY

UNITED STATES PATENT OFFICE.

WILLIAM GILES, OF SAGINAW, MICHIGAN, ASSIGNOR TO A. T. FERRELL & CO., OF SAGINAW, MICHIGAN, A CORPORATION OF MICHIGAN.

TOOL-HOLDER FOR KEY-SEATING MACHINES.

1,279,325.

Specification of Letters Patent. Patented Sept. 17, 1918.

Application filed March 24, 1916. Serial No. 86,428.

To all whom it may concern:

Be it known that I, WILLIAM GILES, a citizen of the United States, residing at Saginaw, in the county of Saginaw and 5 State of Michigan, have invented certain new and useful Improvements in Tool-Holders for Key-Seating Machines; and I do hereby declare the following to be a full, clear, and exact description of the invention, 10 such as will enable others skilled in the art to which it appertains to make and use the same.

This invention relates to key-seating machines and pertains more particularly to an 15 improved construction and arrangement of the tool-holding device, whereby the objects of my invention are attained.

These objects are, first, to provide a tool-holder for key-seating machines that is 20 capable of feeding the cutting tool progressively into the work while supporting the tool in such a manner that chattering and vibration are prevented and the liability of getting particles of metal or dirt between 25 the back of the tool and its supporting surface is eliminated.

Much difficulty has been experienced in 30 practice with key-seat cutters in which the tool-feeding device is so constructed that it is possible for the tool to be fed forward too fast or too far, because of a chip of metal or other obstruction becoming lodged between the face of the feeding wedge and the 35 back of the cutting tool. Such a mishap has frequently been the cause of spoiled work, and has also resulted in breaking the hardened steel tool head from its bar, causing frequent delays and considerable expense for repairs.

40 My present invention avoids these difficulties by providing a mounting and an adjusting or feeding device for the tool, so constructed that it is impossible for the tool to chatter, and also impossible for the tool to be accidentally fed forward by accumulation 45 of dirt on the backing or thrust-resisting support that holds the tool to its work.

With the above and certain other objects in view which will appear later in the specification my invention consists of the devices described and claimed and the equivalents thereof.

5 In the drawings, Figure 1 is a side view broken away in part of the stationary guide that carries the cutting rod.

Fig. 2 is a top plan view of the same.

Fig. 3 is a front view of the vertically movable tool-carrying bar.

Fig. 4 is a side view of the same.

Fig. 5 is a front view of the cutter bar. 60

Fig. 6 is a vertical section on line 6—6 of Fig. 5.

Fig. 7 is a transverse section on line 7—7 of Fig. 6.

Fig. 8 is a perspective view, partly broken 65 away, showing the guide, tool-carrying bar and cutter bar assembled.

As is clearly shown in the drawings, the device consists in a stationary guide post 1 secured to the bed 2 of a key-seating machine in any suitable manner, as by set bolts 70 3. The guide post has a hole 4 of rectangular cross section extending lengthwise from end to end, and a longitudinal slit 5. A vertically movable tool-carrying bar 6, of 75 rectangular cross section is slidably received in the hole 4 of the guide post, and is adapted to be actuated by any suitable power mechanism of the key-seating machine, not shown.

80 The upper end of the tool-carrying bar 6 is formed with a longitudinal slot 7, which divides the upper part of the bar to form two parallel upwardly-extending side members 8, 8, which are slidably received in the 85 rectangular hole 4 of the guide post. The inner faces of the side members 8 are formed with diagonally disposed grooves 9, 9 extending from the upper ends of the side members 8 downwardly and rearwardly, as 90 shown in Fig. 6. Between the two side members 8, 8 a cutter bar 10 is received, the upper end of the cutter bar formed with a cutting tooth 11.

At each side of the cutter bar 10 is a 95 diagonally disposed tongue 12, which is slidably received in the groove 9 of one of the side members 8. It will be understood that the vertically movable tool-carrying bar 6, which travels up and down in the hole 4 of 100 the stationary guide post 1, carries with it the cutter bar 10, the cutting edge of the tooth 11 projecting through the slit 5 and slightly beyond the periphery of the guide post 1, the amount that the tooth projects 105 beyond the guide post determining the depth of the cut.

To feed the tool forwardly or into the work, it is only necessary to project the cutter bar upwardly with relation to the tool 110

carrying bar 6, and to reduce the cut, the cutter bar 10 is drawn downwardly with relation to the tool carrying bar.

The diagonally disposed tongues 12 of the cutter bar 10, in their close engagement with the groove 9 of the side members 8 of the tool-carrying bar 6, effectually prevent springing forward of the tooth 11 and hold the tooth accurately to its adjusted position with relation to the work, while permitting the tooth to be easily and yet positively fed into the work by proper longitudinal adjustment of the bar 10 with respect to the tool-carrying bar 6. This adjustment may be effected by any usual or well-known mechanism for the purpose. Such mechanism is common in key-seating machines and is not illustrated because it forms no part of the present invention.

Since the side members 8 accurately fit the hole 4 in the guide post, there is no chance for dirt or chips to get behind the tooth 11 or behind the side members 8, and thereby feed the tooth into the work too fast. Moreover the tooth 11 is strongly reinforced at its root, which is normally its weakest point, by the projecting tongues 12.

By the means above described I have produced a simple, yet strong and durable tool holding device for key-seating machines that permanently and accurately retains its adjusted position without liability of being

thrown out of adjustment by accumulation of dirt or chips, and consequently does its work with exactness and uniformity.

Having thus described my invention, what I claim and desire to secure by Letters Patent is:

In a tool holder for key-seating machines, a fixed guide post having a longitudinal opening of rectangular cross section therethrough and a longitudinal slit therein, a bifurcated bar of rectangular cross section slidably received in the opening of said guide post, the inner face of each member of said bifurcated bar formed with a diagonally disposed groove extending from the upper extremity of said bar to the rear face thereof, a tool bar slidably received between the members of said bifurcated bar and extending lengthwise thereof, a tooth on said tool bar and a laterally projecting tongue on each side of said bar, said tongues extending from the upper extremity of said tool bar to the rear face thereof and engaging respectively the grooves of said bifurcated bar.

In testimony whereof I affix my signature in presence of two witnesses.

WILLIAM GILES.
